UNITED STATES PATENT OFFICE.

CLAYTON A. BROOKS, OF GIRARD, PENNSYLVANIA.

SAFETY APPARATUS FOR RAILROADS.

1,221,827.

Specification of Letters Patent. Patented Apr. 10, 1917.

Application filed November 16, 1914. Serial No. 872,401.

To all whom it may concern:

Be it known that I, CLAYTON A. BROOKS, a citizen of the United States, residing at Girard, in the county of Erie and State of 5 Pennsylvania, have invented certain new and useful Improvements in Safety Apparatus for Railroads; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

10 My invention relates to safety apparatus and devices for railroads adapted to be automatically operated to stop the train when the speed thereof exceeds the pre-determined maximum, or which may be used to stop a 15 train at a desired station-stop.

20 The object of my invention is to combine in an operative apparatus a piston mechanism adapted to be actuated by air to release the engineer's lever, open an air-release valve, and close the throttle-valve; an automatic pressure controlled valve adapted to be automatically closed when the pressure in the train-pipe has been reduced the desired amount; a valve to control the admission of 25 air to said piston mechanism and the exhaust therefrom; a governor-controlled speed-selective mechanism adapted to operate the said admission valve; and a trip mechanism adapted to remain at a uniform elevation 30 with relation to the rail-way track.

In my application for patent filed February 10th, 1914, Serial No. 817,802, I have shown, described and claimed an apparatus which, in operation is designed to produce 35 similar results to those produced by the apparatus shown and described in this application, but the several mechanisms of the apparatus of my present invention differ in construction and operation from the corresponding parts of the apparatus shown and 40 described in my former application.

The features of my invention are herein-after fully explained and pointed out, and are illustrated in the accompanying drawings, in which:—

Figure 1 is a diagrammatic view of a portion of my apparatus, showing the associated mechanisms thereof in section.

Fig. 2, is a top or plan view of the

throttle-valve operating mechanism of my 55 invention.

Fig. 3, is a rear end view thereof with a portion broken away.

Fig. 4, is a sectional view of the butter-fly valve used in my apparatus. 60

Fig. 5, is a transverse section on the broken line $v-v$, in Fig. 2, looking in the direction of the arrow.

Fig. 6, is a transverse view of the speed-selective mechanism on the broken line w , in 65 Fig. 1, looking in the direction of the arrow.

Fig. 7, is a top or plan view of the same, with the cover broken away.

Fig. 8, is a side view of a portion of the same, showing electro-magnetic mechanism 70 for actuating the same under certain conditions.

Fig. 9, is a sectional view of the opposite side of the speed-selective mechanism of my invention, showing the electric connections 75 and electro-magnetic mechanism.

Fig. 10, is a side elevation of a portion of the same.

Fig. 11, is a side elevation of my improved trip actuated mechanism. 80

Fig. 12, is a rear end view of the same section on the line $x-x$, in Fig. 13.

Fig. 13, is a top or plan view of the same section on the line $z-z$ in Fig. 12.

In these drawings A, indicates a portion 85 of a locomotive boiler; A', indicates a throttle valve-stem; A², indicates a cylinder into which the valve-stem A', extends, and which is supported upon a bracket α , secured upon the boiler A; and within the cylinder A², 90 there is a piston A³, which is adapted to contact with the valve-stem A'. Upon the rear end of the cylinder A², I secure a housing A⁴, which closes the rear end of the cylinder A², and has therein a valve cavity α' , from 95 which an opening α^2 , communicates with the interior of the cylinder A². Within the valve cavity α' , I place a valve A⁵, which is provided with a groove α^3 , in the side thereof, extending from the opening α^2 , to the upper end of said valve, so that air within 100 the cylinder A², may pass out through said groove when the valve A⁵, is in the position shown in Fig. 1. From the lower end of the valve cavity α' , an opening leads into a pipe 105 connection α^4 . At the upper end of the valve A⁵, there is a stem α^5 , which extends upward through a bracket A⁶, and between said

bracket A⁶, and said valve there is a spring adapted to normally maintain said valve in its lower-most position, as shown in Fig. 1. Upon the valve-stem A', I place slidable latch block A⁷ to which the engineer's lever a⁸, is pivoted. In the top of this latch block A⁷, I place a latch bolt A⁸, which is provided with a disk-like collar a⁹, said latch bolt entering a hole or notch in the valve-stem A', as shown in Fig. 5. On the sides of the latch block A⁷, I secure a yoke a⁸, through the upper end of which yoke the upper end of said latch-bolt extends, and upon this latch-bolt between said disk-like collar a⁹, and the yoke a⁸, I place a spring a⁹, which operates to force the latch-bolt A⁸, into its notch in the valve-stem A'. When the latch-bolt A⁸, is in its notch in the valve-stem A' the valve-stem A', can be operated by means of the engineer's lever a⁸, in the usual manner. Mounted along-side of the cylinder A², there is a rock-lever A⁹, one end a¹⁰, (see Figs. 2 and 3) of which projects over the upper end of the valve A⁵, and the other end of said rock-lever A⁹, extends over the latch-block A⁷, under the disk-collar a⁹, so that when the valve A⁵, moves upward, it actuates the rock-lever A⁹, to raise the latch-bolt A⁸, out of engagement with the valve-stem A', so that the latch-block A⁷, will slide freely on the valve-stem A', and thus it will be impossible for the engineer to operate the valve-stem by means of his lever a⁸. Above the bracket A⁶, I place an air-release valve-housing B, having seated in the bottom thereof, and concentric with the valve A⁵, a valve B', adapted to be raised off of its seat by the stem a⁵, when the valve A⁵, is raised upward. The valve-housing B, is provided with a pipe connection b, which communicates with the interior thereof. The housing B, is supported in position by means of a bracket B², secured to the housing A⁴. From the pipe connection b, on the air-release-valve-housing B, a pipe 1, leads to the train pipe 2, through an automatic pressure-regulated valve-housing C. This valve-housing C, is provided with a valve-seat opening C', upon which a valve C², operates. The valve C², is provided with stems c and c'. In the housing C, I provide an adjusting screw C³, and between said screw and the stem c, I place a spring c². The opposite end of the valve-housing C, is provided with a diaphragm chamber C⁴, in which there is secured a diaphragm C⁵, to which the valve-stem c', is secured. The diaphragm chamber C⁴, communicates through the pipes 3 and 4, with the main air pipe 5, so that when air from the train pipe 2, has passed through pipe 1, and the valve-housing C, until a sufficient amount has escaped to reduce the pressure on the valve-side of the diaphragm C⁵, to allow the air on the opposite side of the diaphragm to

press the spring c², backward and close the valve C², the escape of air from the train pipe 2, will be automatically stopped.

The valve-housing A⁴, is connected to the main air supply pipe 5, by means of the pipes 6 and 7, through a valve-housing D. This valve-housing is provided with two valve-chambers D' and D², the chamber D', communicating with the pipe 6, and the chamber D², communicating with the pipe 7. In the chamber D', there is a valve d seated upon a valve-seat d', with its stem d², extending into the chamber D², so that said valve is held upon its seat by the pressure of air within the chamber D'. Within the chamber D², I mount a bell-crank-lever D³, one arm of which is secured to the valve-stem d².

Pivoted upon the other arm of said lever D³, is a valve-stem d³, which extends through a valve-opening d⁵, in the wall of the chamber D²; the outer end of the valve-stem d³, is pivoted to a lever D⁴, which lever is pivoted to ears d⁴, on the outside of the chamber D².

Upon the valve-stem d³, I place a valve D⁵ 90 adapted to seat upon the valve-seat opening d⁵. By operating the lever D⁴, the valve D⁵, is closed upon its seat d⁵, and the valve d, raised off of its seat d', so that air can pass from the pipe 6, through the chambers D' and D², into the pipe 7. It may be found desirable to provide the valve-stem d³, and valve D⁵, with a resilient support D⁶, so that after the valve D⁵, is seated upon its seat d⁵, the valve stem d³, may be moved a little farther, and thus avoid breakage.

E, indicates the usual engineer's air valve. In the pipe 4, leading from the main air supply pipe 5, through the engineer's valve E, to the train pipe 2, I place an ordinary butter-fly valve E', (see Fig. 4) and I provide mechanism for operating said valve, consisting of a cylinder E², which communicates with the pipe 7, by means of the pipe 8. In this cylinder there is a piston e, the piston-rod e', of which is connected with the arm e², of the butter-fly valve E'. I also provide a spring e³, to maintain the piston and valve in the normally open position shown in Figs. 1 and 4. By means of this valve E', and its operating mechanism, when air is admitted into the pipe 7, it also enters the cylinder E², through the pipe 8, and the piston e operates to close the butter-fly valve E', so that communication from the main air supply pipe 5, through the pipe 4, is closed by said butter-fly valve E', so that the pressure in the train pipe 2, can be reduced by the opening of the air escape valve B'.

For operating the lever D⁴, to open the valve d, and close the valve D⁵, I provide a rock-shaft F, which is mounted in the walls of the box-frame F'. Upon this rock-shaft F, I secure an arm F², which is in connection with the lever D⁴, by means of the bar F³. 130

Upon the rock-shaft F, I secure a plurality of levers F⁵, preferably forked at their ends f. On the end of the rock-shaft F, I place a crank F⁶ (see Figs. 6 and 10) and to the 5 wrist-pin f', of this crank, which is off of the center line of the crank, I secure one end of a spring f², the other end of said spring being secured to a post f³, secured in the wall of the box-frame F'. The operation of 10 the spring f², being to retain lever F⁵, in its upward position as shown in Fig. 1, or when it is moved downward, as hereinafter described, to retain it in its downward position, until it is manually returned to its 15 upward position, thereby maintaining the valve d, open and the valve D⁵ closed until they are thus manually reversed. Vertically mounted in the box-frame F', there is a plurality of slidable rods G, G', G², and G³, 20 which rods are embraced by the forked ends f, of the arms F⁵.

Upon each of said rods G, G', G² and G³, is secured a cross-arm g, which contacts with the upper side of the arms F⁵. The rod 25 G, is provided with a rigid shoulder g'. Upon the upper ends of the rods G, G', G² and G³, there are heads g², between which and the top of the box-frame F', are springs g³, for the purpose of maintaining said rods 30 in a normally upward position as shown in Figs. 1 and 9. The rods G', G² and G³, are provided with swinging bars G⁴, the lower ends of which are pivoted to said rods by means of pivot-pins g⁴, (see Fig. 9). Between the lower ends of said bars G⁴ and the cross-bars g I place springs g⁵, which operate to press the upper ends of the bars G⁴, toward the rods 35 G', G² and G³. Slidably mounted in the 40 rods G', G² and G³, are transverse pins g⁶, provided with heads which are engaged by the upper ends of the bars G⁴, and are thereby pressed against the rods G', G² and G³, and which heads limit the forward 45 movement of said pins. The bars G⁴, are provided with shoulders g⁷. Upon the lower end of the rods G, G', G² and G³, I secure collars g⁸, to limit the upward movement of 50 said rods. Adjacent to each of rods G, G', G² and G³, I mount in said frame F', another vertically slidable rod H, H', H² and H³, each of which is provided with a head h, on the upper end thereof, and between 55 said heads and the frame F', I place springs h' to maintain said rods in their normally upward position, as shown in Figs. 1 and 9. Upon the lower ends of said rods H I place 60 collars h² to limit the upward movement of said rods. Each of the rods H, H', H² and H³, is provided with a transverse bar H⁴, which is preferably pivoted thereto and provided with a spring h³, thereby providing 65 said cross bars H⁴, with a limited tipping movement when required during the upward movement of said rods H. These cross bars

H⁴, are adapted to engage the rigid shoulder g', on the rod G, and the shoulders g⁷, on the bars G⁴, when the rods H, are moved downward, under conditions hereinafter described, and thereby force the rods G, G', 70 G², and G³, to move downward in unison therewith, and thereby, through the arms F⁵, operate the valves d, and D⁵, as hereinbefore described. To the lower ends of the rods H, H', H² and H³, are secured wires 75 J, J', J², (see Fig. 7) which are connected with trip mechanism hereinafter described, whereby each of said rods H, H', and H², may be operated as described. The lower end of the rod H³, is connected to an electro- 80 magnetic device J⁸, (see Figs. 7 and 9) by which the same may be operated as hereinafter described.

Within the frame F', I mount longitudinally slidable rods K, K' and K², each of 85 which is in line with the rods G', G², and G³. On one end of each of these rods K, K', and K², are flat heads h, h', and h², against which the pins g⁶, contact. The rods K, K' and K², are provided with springs k³, to normally maintain the heads h, h', and h², 90 against the supports K³, of the rods K, K', and K², which supports are secured upon the bottom of the frame F'. Contacting with the other end of the rods K, K', and K², there are vertical swing-bars, L, L', and L², each of which is provided with a shoulder l, for the purpose hereinafter described. Within the frame F', upon vertical rods L⁴, I slidably mount a plate L⁵, which is provided with slots l', and upon this plate L⁵, I adjustably secure vertical cam-bars l², l³ and l⁴, each having a cam surface l⁵ thereon adapted to engage one of the shoulders l, on 100 one of the swinging bars L. These cam-bars are secured upon the plate L⁵, by means of stud-bolts l⁶, passing through the slots l', in said plate, and the thumb-nuts l⁷. To move the plate L⁵, vertically, I provide a 105 centrifugal governor mechanism M, of ordinary construction, which is operated by the flexible shaft M', through the gears M², said shaft M', being connected to gears upon the trip mechanism hereinafter described. The cam-bars l², l³, and l⁴, are vertically adjusted upon the plate L⁵, so that their cam- 110 surfaces l⁵, will each engage the shoulder l, on its corresponding swinging bar L, and push its corresponding rod K, K' or K² forward and thereby move the corresponding shoulder g⁷, forward to be engaged by its corresponding transverse bar H⁴, when the 115 governor mechanism M, is revolving at the relative speed for which said cam-bars are adjusted, so that when the trip mechanism hereinafter described is operated, while the train is moving at that rate of speed, to pull one of the rods H', H² or H³, downward, its transverse bar H⁴, will engage the shoulder g⁷, of the bar G⁴, which has been pushed 120

125 hereinafter described is operated, while the train is moving at that rate of speed, to pull one of the rods H', H² or H³, downward, its transverse bar H⁴, will engage the shoulder g⁷, of the bar G⁴, which has been pushed 130

forward, and thereby cause the rod G' , G^2 or G^3 , whose bar G^4 , has been swung forward to move downward until its pin g^6 , springs back under the head k , k' or k^2 , which locks 5 said rod in its downward position until it is released by the backward movement of that particular head permitted by a slowing down of the speed of the governor M , caused by the opening of the valve d , and the admission 10 of air therethrough into the cylinder A^2 , and the resulting setting of the train brakes as hereinbefore described. To release the mechanism it is necessary to manually reverse the crank F^6 (see Fig. 10) as hereinbefore described.

When the train reaches its speed limit the plate L^5 , will be moved by the governor M , to its lowermost position, which will, through the cam-bar l^4 , swing bar L^2 , sliding rod K^2 , push the pin g^6 , and bar G^4 , associated with the vertical rod G^3 , toward the vertical rod H^3 , so that the bar G^4 , will be engaged by the transverse bar H^4 , in the rod H^3 . At the same time the point l^8 , on 20 the plate L^5 , will press one pole m , of an electrical contact down upon the other pole, m' , of said contact, and complete the circuit m^2 , through a generator and the electromagnetic device J^3 , which will then exert sufficient force upon the rod H^3 , to draw it 25 downward and carry with it the rod G^3 , and thereby, through the arm F^6 , cause the valves d , and D^5 , to be operated to admit air to the throttle-valve closing mechanism 30 hereinbefore described. For breaking the circuit m^2 , when the rod G^3 , is moved downward, and before the plate L^5 , releases the contact m , I have provided two terminal contact posts m^3 , which are bridged by a plate m^4 , contacting therewith. This plate m^4 , is secured to a lever m^5 , pivoted upon a post m^6 . Under the other end of the lever m^5 , there is a spring m^7 , to normally keep the plate m^4 , in contact with the contact terminals m^3 . The transverse arm g , on the rod G^3 is provided with a lateral extension m^8 , which, when said cross-bar is in the position thereof shown by broken lines in Fig. 9, 35 will engage the lever m^5 , and raise the plate m^4 , thereby breaking the contact m^3 to release the rod H^3 , and permit it to rise to its normal position.

Meanwhile, the speed of the train having 40 been reduced, the governor M will raise the plate L^5 , so as to allow the contacts m and m' , to separate, thereby breaking the circuit at that point, and at the same time the raising of the plate L^5 , through the intermediate mechanism will release the rod G^3 , and permit the spring m^7 , to again close the circuit at the terminal m^3 , thereby restoring said circuit to its original condition with but one break therein. The object of the break in the circuit at terminals m^3 , is to avoid the continued use of the generator during the

time the train is slowing down, and thereby avoid frequent renewals of the generator, as the work of the generator is accomplished as soon as the rod G^3 , has been moved downward, and the arm F^6 , operated thereby. It 70 will be understood that this electric apparatus is only operated when the train has exceeded its speed limit, solely by the action of the governor. It is likewise to be understood that the rods G and H , are operated 75 only at station stops, without regard to any particular rate of speed, and are therefore not provided with mechanism actuated by the governor for communicating their motion to the valves d and D^5 , but always operate those valves when they are moved downward. 80

In Figs 11, 12 and 13, I have illustrated my improved trip mechanism the construction of which is as follows, viz:—

85

In a frame N , upon a shaft N' , I mount a wheel N^2 , adapted to engage one of the rails n , of the rail-road track. Upon the shaft N' , I secure a miter-gear N^3 . In the frame N , I mount a short shaft at right angles to said shaft N' , upon which there is a miter-gear n' which intermeshes with the gear N^3 . Upon the opposite end of said short shaft there is another miter-gear wheel n^2 ; across one end of the frame N , there is a rod O , by which the frame N , is hinged to the supporting arms O' O' , which are rigidly secured to the frame of a locomotive. The arms O' O' , are provided with a cross-brace O^2 , (see Fig. 12). Upon the shaft O , 100 I mount miter-gear wheels o and o' , which are connected by a sleeve o^2 , the wheel o , of which intermeshes with the gear n^2 . Journaled in the cross-brace O^2 , is the lower end 105 of the governor-shaft M' , upon which is secured a miter-gear wheel o^3 , so that as the wheel N^2 , travels along the rail n , the train of gears N^3 , n' , n^2 , o , o' , and o^3 , will, through the shaft M' , operate the governor.

Mounted upon the rod O , are bell-crank 110 levers P , P' , and P^2 , (see Fig. 13) to which the wires J , J' and J^2 , which are connected to the rods G , G' and G^2 , hereinbefore described (see Fig. 8). Suspended to the frame N , under the shaft N' , are levers p , p' 115 and p^2 , which extend downward slightly above the upper faces of the rails n .

Between the lower arms of the bell-crank levers P , P' and P^2 , and the levers p , p' and p^2 , are pivoted connecting bars Q . 120

From the foregoing description of my improved traveling trip mechanism, it will be seen that although the frame of the locomotive may compress its supporting springs more or less, and thereby be nearer to the 125 tracks than at other times, the distance from the bell-crank levers to the box-frame F' , of my apparatus never varies after installation, and the wires J , J' and J^2 , never become slack. Likewise, while for conven- 130

- ience of the drawings I have shown a flexible governor shaft M', an ordinary metal shaft may be used. And further the trip levers p , p' and p^2 , are maintained at a 5 uniform elevation with relation to the rails n.
- For operating the levers p , p' and p^2 , I place on the ties R, where it is desired to stop trains at stations, a manually operated trip S, which is pivoted in a frame S', and 10 under this trip S, I secure a crank S², which is secured upon a shaft S³, suitably supported upon the ties R. Between the crank S², and the trip S, a link S⁴, is pivoted, so that when it is desired to stop the train at that 15 station the shaft S³, is operated to raise the trip S, upward as shown in Fig. 11, so that it will engage the lever p , which, through the bell-crank lever P, and wire J, will pull the rods H and G, downward, and then operate the valves d and D⁵, thereby causing 20 the train to stop as hereinbefore described. Now, it may be that at some point on the road it is desired that the train shall not run at, say twenty-five miles an hour. In that 25 case, a stationary trip T, (see Figs. 11 and 12) is placed at such a place, in a position where it will engage the lever p' , the cam-bar l², on the plate L⁵, being adjusted for that speed. Now, if the train is running at 30 twenty-five miles an hour, the governor M, will lower the plate L⁵, so that the cam-bar l², will, through the intermediate mechanism hereinbefore described, move the bar G⁴, on the vertical rod G', toward the vertical rod G⁴ the lever p' , engaging the trip T, will, through the bell crank lever P', and wire J', cause the train to stop as hereinbefore described. And again, if at another 35 point of the road it is deemed that a speed of say thirty-five miles an hour is dangerous, a stationary trip T', is placed at such a point in a position to engage the lever p^2 , the cam-bar l³, on the plate L⁵, being adjusted for that speed; if the train is running at 40 thirty-five miles an hour when the lever p^2 , engages the trip T', the same operation of mechanism takes place and the train is stopped.
- In the case of all stops due to the operation of mechanism hereinbefore described, the crank F⁶, on the rock-shaft F, will have 45 to be manually reversed to its normal position as shown by full lines in Fig. 10, before the train can be started.
- Having thus fully described my invention and the construction and operation of suitable mechanism for embodying it, what I claim as new and desire to secure by Letters-Patent, is:-
1. In an apparatus of the character described, a throttle-valve stem having a notch therein, a latch-block slidably mounted thereon, a latch-bolt slidably mounted in said block and adapted to enter the notch in said 50 valve-stem, a yoke secured on said latch-block, to support the outer end of said latch-bolt, a shoulder on said latch-bolt, a spring between said yoke and said shoulder to normally maintain said latch-bolt in said notch, a rock-lever adapted to engage said shoulder 70 to raise said latch-bolt out of engagement with said notch, and pneumatic mechanism to operate said rock-lever substantially as set forth.
2. In an apparatus of the character described, 75 a throttle-valve stem, cylinder and piston mechanism adapted to actuate said valve-stem to close the valve connected therewith, a piston valve adapted to be actuated by air to admit air to said cylinder and piston mechanism, a stem on said piston-valve, an air escape valve communicating with the train air pipe adapted to be engaged and opened by the stem on said piston-valve, and means to admit air to said piston-valve when desired, substantially as 80 described.
3. In an apparatus of the character described, 85 a throttle-valve-stem, cylinder and piston mechanism to actuate said valve-stem to close the valve connected therewith, a valve-housing having a valve-chamber therein, an inlet valve to admit air into said chamber, a spring pressed outlet valve in said chamber at right angles to said inlet valve to allow air to exhaust therefrom, lever mechanism adapted to close said exhaust valve and open said inlet valve, means to supply air to said inlet valve, and means to conduct air from said valve-chamber to 90 said cylinder and piston mechanism, substantially as set forth.
4. In an apparatus of the character described, 95 a valve mechanism comprising substantially a chamber, a valve seated exterior to said chamber to admit air thereinto, a spring pressed valve seated within said chamber at right angles to said inlet valve adapted to permit air to escape therefrom, a lever mounted within said chamber and connected with each of said valves and adapted to close said exhaust valve and open said admission valve, and means to 100 operate said lever, substantially as set forth.
5. In an apparatus of the character described, 105 a cylinder and piston mechanism for closing the throttle-valve of a locomotive, a pneumatic valve adapted to be actuated to admit air to said cylinder and piston mechanism, an air-escape valve 110 adapted to be opened by said pneumatic valve, means to admit air to said pneumatic valve, a diaphragm chamber, an air connection from the train pipe to said diaphragm chamber and therefrom to said air-escape valve, a diaphragm in said chamber, 115 a valve in said chamber adapted to be actuated by said diaphragm to close said valve, a spring adapted to actuate said valve in the opposite direction, means to adjust the ten- 120
- 60 65 70 75 80 85 90 95 100 105 110 115 120 125 130

sion of said spring, and an air connection between the opposite side of said diaphragm chamber and the main source of air supply, substantially as set forth.

- 5 6. In an apparatus of the character described, pneumatic mechanism adapted to close the throttle-valve of a locomotive, a pipe connected thereto and leading to a source of compressed air, a valve mechanism therein to control the admission of air to said pneumatic mechanism, lever mechanism to actuate said valve mechanism, a vertical spring pressed slide means on said slide adapted to operate said lever mechanism, a 10 second spring pressed slide trip actuated mechanism, means to connect said second spring-pressed slide with said trip-actuated mechanism, means on said second spring pressed slide to engage said first mentioned 15 spring pressed slide and a trip located on a rail-road track adapted to engage and actuate said trip actuated mechanism, substantially as set forth.

- 20 7. In an apparatus of the class described, 25 pneumatic mechanism adapted to close the throttle-valve of a locomotive, valve mechanism adapted to control the admission of air to said pneumatic mechanism, spring pressed slide mechanism, trip actuated mechanism, means to connect said trip actuated mechanism with said spring pressed slide mechanism, speed controlled selective mechanism adapted to be engaged by said 30 spring-pressed slide mechanism, and lever mechanism adapted to be actuated by said selective mechanism to operate said valve mechanism to admit air to said pneumatic mechanism, substantially as set forth.

- 35 8. The combination in a speed-selective 40 mechanism of an air-controlling valve, lever mechanism to actuate said valve, a spring-pressed slide, a lateral projection mounted on said slide, a second spring-pressed slide adjacent to the first mentioned slide, a 45 transverse sliding pin mounted therein, a spring-pressed bar pivoted upon and parallel with said second spring pressed slide and contacting with said pin, a horizontal spring-pressed slide mechanism engaging

the opposite end of said pin, a swinging 50 vertical bar engaging the opposite end of said horizontal slide mechanism, a shoulder on said bar, a vertically movable cam-bar adapted to engage said shoulder, a centrifugal governor mechanism adapted to control the movement of said cam-bar, and trip mechanism adapted to actuate said first mentioned spring-pressed slide, substantially as set forth.

55 9. The combination in a speed-selective 60 mechanism, of a centrifugal governor, means to operate the same, a vertical slide-able plate, a cam-bar adjustably secured upon said plate, a horizontal spring-pressed slide mechanism adapted to be actuated in 65 one direction by said cam-bar, a vertical spring-pressed slide, a transverse slideable pin therein adapted to be operated by said horizontal spring-pressed slide, a spring-pressed swinging bar on said vertical spring-pressed slide engaging said transverse pin to operate the same in the opposite direction, a valve, lever mechanism adapted to 70 actuate said valve, means on said vertical slide to engage and actuate said lever mechanism, a spring-pressed trip actuated slide, a lateral projection mounted thereon adapted to engage the swinging bar on the first mentioned vertical slide when said bar has been moved toward the trip actuated slide 75 by the governor controlled mechanism, substantially as set forth.

80 10. In a speed-selective mechanism, a valve, lever mechanism to operate the same, governor controlled and trip actuated mechanism adapted to actuate said lever mechanism to open said valve, and mechanism including spring actuated crank and shaft mechanism adapted to maintain said valve open until manually released, substantially 85 as set forth.

90 In testimony whereof I affix my signature, in presence of two witnesses.

CLAYTON A. BROOKS.
